E. W. Marshall

UNITED STATES PATENT OFFICE.

THOMAS BRADY, OF WOODCLIFF, NEW JERSEY.

DOOR-OPERATING DEVICE.

1,403,481.

Specification of Letters Patent. Patented Jan. 17, 1922.

Application filed December 18, 1919. Serial No. 345,799.

To all whom it may concern:

Be it known that I, THOMAS BRADY, a citizen of the United States of America, and a resident of Woodcliff, Bergen County, and 5 State of New Jersey, have invented certain new and useful Improvements in Door-Operating Devices, of which the following is a specification, reference being had to the accompanying drawing, forming a part 10 thereof.

This invention relates to improvements in door operating devices, and especially for such as are used as a part of elevator closures. Its object is to provide a simple, inexpensive and effective arrangement by 15 means of which the door may be locked in its closed position, may be opened easily by an operator and will close automatically.

Another object is to so construct the parts 20 that they may be easily installed in the narrow space between an elevator hatchway closure and an elevator car. Further objects are to provide a simple arrangement for adjusting the closing springs, and to so construct 25 a dash pot as to make it leak proof.

These and other objects of the invention will appear in the following specification in which I will describe my invention and the 30 novel features of which will be set forth in appended claims.

Referring to the drawings:

Figure 1 is an elevation of an elevator door with a mechanism applied thereto which is made according to and embodies 35 this invention. In this figure the door and its associated parts are shown in full lines in the positions which they assume when the door is closed, and the positions which some of the parts assume when the door is 40 open are indicated by broken lines.

Figure 2 is a sectional end elevation of the parts shown in Figure 1, the section being taken on the line 2—2 of Figure 1.

Figure 3 is a sectional elevation of the 45 improved dash pot.

Like characters of reference designate corresponding parts in all the figures of the drawing.

10 designates a stationary part of an elevator hatchway closure, and 11 a sliding door. 12 is the threshold or a part of the floor. The mechanism which I have shown as an embodiment of this invention comprises a housing 20 which is affixed to the 50 threshold 12 between the hatchway closure and the path of the elevator car. Pivoted 55

to this housing is a gear sector 22 having a radially projecting holder or stub-arm 24' within or to which is fixedly secured a member which together with the sector constitutes a swinging lever 23. This lever extends upwardly through a strap 24 pivoted on the elevator door, the strap being slightly wider than the lever at that point whereby a lost-motion connection is provided. The 60 lever is notched as at 25 to engage with a pin 26 fixed to the strap 24, the upper end of the lever terminating in a handle 27. This arrangement provides a simple locking means between the door and swinging lever 65 as will be readily understood. Projecting from one side of the stub-arm 24', for a purpose hereinafter mentioned, is a pair of ears 28.

The housing 20 is constructed with an 75 upstanding rib provided with holes which receive the lower ends of a plurality of spiral springs 32. The upper ends of these springs are secured to loops 33 which surround the arm 31 and through the upper ends 80 of which are threaded adjusting bolts 34 whereby the tension of the springs may be varied.

If desired an automatic cut-out switch 38 may be mounted on the housing and connected by a link 39 with the arm 31 and arranged to be operated thereby.

40 designates a dash pot, the lower end 41 of which is pivoted to the housing 20. 42 is a piston within this dash pot and 43 is 90 a ball check valve in the piston. A piston rod 44, which passes through a stuffing box 45 extends between the ears 28, on the stub-arm 24' of the sector 22 and is held in position therebetween by a pin 46. The upper 95 end of the piston rod is threaded to receive adjusting nuts 47 on either side of the ears 28. 48 is a by-pass from the lower end of the cylinder of the dash pot to a port 49 near the upper part of the dash pot. 50 is a valve seat in the by-pass below port 49 and 51 a threaded shank of a needle valve which is adapted to screw into an extension of the by-pass above port 49. This dash pot is constructed to operate with oil and the oil level 100 therein is shown at 52.

I will now describe the manner in which this device operates. Let us assume that the parts are in the positions in which they are shown in full lines in Figure 1. The elevator door 11 is then locked because of the 110 fact that the pin 26 in the strap 24 is in

engagement with one of the notches 25 in the lever 23. However, since the strap 24 is somewhat wider than the lever 23 it is possible to lift the lever 23 away from the 5 pin 26 thus unlatching the door. The lever is first lifted clear of the pin 26 and a continued movement to the right will cause the door to be moved back to the position in which it is shown in dotted lines. This 10 movement will be increasingly opposed by the springs 32 but at the same time the leverage increases as the door opens by reason of the lever sliding up into the strap 24.

The engagement of gear teeth 22 with the 15 gear segment 30 will cause the arm 31 to be raised during the opening movement of the door to thereby increase the tension on the springs 32. During the opening movement of the door the piston in the dash pot 20 will move, without opposition, toward the upper end of the cylinder since the check valve 43 during this movement is forced away from its seat by the liquid passing down through the piston as will be readily 25 understood.

As soon, however, as the operator lets go of the handle 27, the springs 32 pull down on arm 31 and thereby rotating the sector 22 and swing the lever 23 in a direction to 30 close the door. This movement will be opposed by the dash pot the check valve 43 closing the port within the piston which consequently can only descend at a rate determined by the pressure exerted by the springs 35 and by the rate at which the oil is able to pass through the by-pass 48 past the needle valve and into the dash pot above the piston through port 49. By keeping the oil level low, two functions are obtained:—first, the 40 initial movement of the lever 23 and of the elevator door will not be materially opposed because piston 42 at first will be moving through air; second, because the regulating valve at all times will be above the oil level 45 and oil tight because the thread of the shank of the needle valve is never subjected to oil under pressure. In fact, as soon as the oil passing through the by-pass past the needle valve reaches the port 49, it may 50 flow freely into the cylinder and therefore has no tendency to go out through the threaded hole into which the needle valve shank 51 fits.

When the door has nearly reached its 55 closed position, the first of the notches 25 will come into engagement with the pin 26 thereby preventing the door from being opened even though the same should not be completely closed.

60 If, as is often desired, a cut-out switch is used in connection with the door operating mechanism, such a switch as that shown at 38, may be employed. It is obvious that the link 39 connecting arm 31 with this switch

will actuate the switch and the circuit may 65 be so arranged that it will be impossible to start the car until the door is closed.

From the foregoing description, it may be seen that the whole apparatus occupies a very narrow space, such as that found in 70 most existing elevator installations, and that it lends itself to easy and quick installation. It is also evident that the springs 32 may be readily adjusted to provide the desired amount of closing pressure upon lever 23. 75 This closing pressure is continually exerted upon the door which when open to any extent will be closed thereby and locked in the manner described. The dash pot will prevent the door from slamming closed, as 80 it will exert a strong retarding effect upon the closing pressure of lever 23 at the end of its door closing movement.

Variations in the construction and arrangement of parts may be made within the 85 spirit and scope of this invention, and I intend no limitations other than those imposed by the appended claims.

What I claim is:

1. A door operating device comprising a 90 swinging lever arranged for connection with a door near one end, a plurality of springs connected in the plane of the movement of the lever arranged to swing the lever in the direction to close the door, 95 and a dash pot in alinement with the lever and the springs and connected with the lever arranged to retard the movement thereof in the door closing direction and arranged to swing in a plane parallel 100 with the plane of the movement of the lever.

2. A door operating device comprising a 105 housing, a swinging lever pivoted in the housing and arranged for connection with a door near one end, an arm pivoted in the housing geared to the lever, and a plurality of actuating springs connected with the arm and with the housing.

3. A door operating device comprising a 110 housing, a swinging lever pivoted in the housing and arranged for connection with a door near one end, an arm pivoted in the housing geared to the lever, a plurality of actuating springs connected with the 115 arm and with the housing, and means for adjusting said springs.

4. A door operating device comprising a housing, a swinging lever pivoted in the housing and arranged for connection with a 120 door near one end, an arm pivoted in the housing geared to the lever at one side thereof, a plurality of actuating springs connected with the arm and with the housing, and a dash pot on the other side of 125 the lever pivoted to said housing.

5. In a door-operating device, the combination with a support, a pair of levers

- pivoted thereto, means for swinging the levers in unison in opposite directions, one of the levers being connected to a door, and means connected to the other lever for moving it about its pivot.
6. In a door-operating device, the combination with a support, a pair of levers pivoted thereto, means for swinging the levers in unison in opposite directions, one of the levers being slidably connected to a door, and means connected to the other lever for moving it about its pivot.
7. In a door-operating device, the combination with a support, a pair of levers pivoted thereto on parallel axes, means for swinging the levers in unison in opposite directions, one of the levers being connected to a door, and means connected to the other lever for moving it about its pivot.
8. In a door-operating device, the combination with a support, a pair of levers pivoted thereto on parallel axes to swing in a common plane, means for swinging the levers in unison in opposite directions, one of the levers being connected to a door,
- and means connected to the other lever for moving it about its pivot.
9. In a door-operating device, the combination with a support, a pair of levers pivoted thereto on parallel axes, means for swinging the levers in unison in opposite directions, one of the levers being connected to the other lever for moving it about its pivot, and means connected to one of said levers for cushioning said last-named means.
10. In a door-operating device the combination with a support, of a pair of levers pivoted to swing about parallel axes in unison in opposite directions, a dash pot pivotally connected to one of said levers and to the support on axes parallel to the first-named axes, resilient means connected to one of said levers to turn the same about its pivot, said dash pot serving to prolong the action of the resilient means, and means slidably connecting one of said levers to a door.

In witness whereof, I have hereunto set my hand this 13th day of December, 1919.

THOMAS BRADY.
